UNITED STATES PATENT OFFICE.

WILLIAM E. DURHAM, OF NORFOLK, VIRGINIA, ASSIGNOR TO THE EMORY RUBBER SOLE CO., INC., OF NORFOLK, VIRGINIA, A CORPORATION OF VIRGINIA.

DESIGN FOR A SHOE-HEEL.

55,158.

Specification for Design.

Patented May 18, 1920.

Application filed January 15, 1920. Serial No. 351,622. Term of patent 7 years.

To all whom it may concern:

Be it known that I, WILLIAM E. DURHAM, a citizen of the United States of America, residing in the city of Norfolk, county of Norfolk, State of Virginia, have invented a new, original, and ornamental Design for a Shoe-Heel, of which the following is a specification, reference being had to the accompanying drawing, forming part thereof.

Figure 1 is a plan view in perspective, and

Fig. 2 is a longitudinal view in perspective, showing my improved design.

I claim:—

The ornamental design for a shoe heel as shown.

WILLIAM E. DURHAM.
